UNITED STATES PATENT OFFICE.

FREDERICK HELMICK, OF FAIRMONT, WEST VIRGINIA.

JOURNAL-BOX.

950,391.

Specification of Letters Patent. Patented Feb. 22, 1910.

Application filed April 19, 1909. Serial No. 490,792.

To all whom it may concern:

Be it known that I, FREDERICK HELMICK, citizen of the United States, residing at Fairmont, county of Marion, and State of West Virginia, have invented certain new and useful Improvements in Journal-Boxes, of which the following is a specification, reference being had therein to the accompanying drawing.

This invention relates to a journal box, and particularly to a lubricating box through which the axle extends for the attachment of the wheel at the outer end of said box.

An object of the invention is to provide a novel and improved arrangement of the lubricating chambers so that the packings therein may feed the lubricant through the bearing block to the upper surface of the axle and also from the lower chamber to the under surface of the axle, this latter chamber being provided with an inlet opening disposed at one side of the axle for the convenient application and removal of the packing material and lubricant therefor.

Other and further objects and advantages of the invention will be hereinafter fully set forth and the novel features thereof defined by the appended claims.

In the drawing:—Figure 1 is an elevation showing the application of the invention to a truck or car; Fig. 2 is a front elevation of the box; Fig. 3 is a vertical section on line 3—3, Fig. 2; Fig. 4 is a similar section at a right angle to Fig. 3; Fig. 5 is a top plan of the box; Fig. 6 is a side elevation thereof; Fig. 7 is a front elevation of a modified form of the invention.

The numeral 10 designates the box which may be of any desired size or configuration and preferably formed as a casting, although it may be otherwise constructed. The box is provided at its upper portion with a longitudinally extending depending bearing seat 11 preferably of suitable configuration to prevent transverse or rotative movement of the bearing block therein. This seat is formed by a depending wall 12 at one side and a corresponding parallel wall 13 at the opposite side. At the inner end of the seat a depending wall 14 is provided which forms an abutment for the bearing block 15. The wall 14 is provided with an aperture 16 through which the axle 17 is adapted to pass. The block 15 may be formed of brass or any other desired wearing material and has the

apertures 18 therethrough to permit a feed of lubricant to the upper portion of the axle 17. This block is retained within the box by the hub 19 carried by the wheel 20 which is secured to the outer end of the axle by any desired means, for instance, the pin 21, as shown in Fig. 1. If desired, the outer end of the box may be formed with a circular recess 22 into which the end of the hub 19 extends so as to contact with the end of the block 15 and prevent longitudinal movement thereof in the box. The upper portion of the box is provided with apertured securing flanges 23 by which the box may be secured to the truck or car 24. One means for thus attaching the box comprises the bolts 25 extending downward through said flanges 23 on a wearing plate 26. The front portion of the box may also be provided with a raised lug 27 adapted to engage the front of the car frame to prevent longitudinal movement of the box and relieve the strain on the securing bolts.

The box is provided at its upper portion with a reservoir 28 at one side thereof and extending longitudinally of the box. This reservoir is provided with an opening 29 at one end by which lubricant may be introduced and is filled with the usual packing, as shown in Fig. 4. Extending laterally through the box is a feed passage 30 which communicates with the bearing seat 11 at substantially its midlength and feeds the lubricant to the apertures in the bearing block disposed in said seat. The lower portion of the reservoir 28 is disposed below the passage 30 and also the apertures in the block so as to retain a body of oil therein. The lower portion of the box is formed with a reservoir 31 adapted to contain a packing and lubricant, the former being in contact with the under surface of the axle. The reservoir 31 is extended laterally at one side of the bearing to form a packing chamber 32 which permits the convenient application and removal of the packing from the reservoir and also the introduction of the lubricant thereto. The chamber 32 may extend longitudinally for the length of the box and is provided at one end with a filling opening 33 adapted to be closed by the pivoted door or cover 34 which is shown in Fig. 2 as disposed at the front of the box and at one side of the bearing therein.

In Fig. 7 a modified form of box is shown in which the mounting for the bearing and

the disposition of the lubricating reservoir are the same as previously described, while the inlet opening to the packing chamber 32 is disposed at one side of the bearing instead 5 of at the front thereof, and the door 35 pivotally mounted to close the opening to this chamber. In this form of the invention the casing 36 carrying the parts of the box is adapted to be secured by apertures 37 extending therethrough, through which ordinary securing bolts may be applied.

In the operation of the invention it will be seen that the bearing block can be conveniently removed and replaced without disturbing the axle by simply removing the wheel from the end thereof, and when secured in position by the wheel all longitudinal movement of the block is prevented and it is thus held in accurate position without 15 the necessity of other fastening or securing devices. This mounting also permits the block to be slid directly into its seat and held therein against lateral movement. The arrangement of the reservoirs provides 20 means for continuously lubricating the surfaces of the axle which rotates within the bearing and maintains a feed of lubricant thereto. The arrangement of the packing 25 chamber permits convenient access to the packing beneath the entire length of the bearing so that it can be readily removed and replaced as desired.

It will therefore be seen that the invention 30 presents a simple, efficient and economically constructed form of lubricating bearing particularly adapted for use in mine and railway cars or trucks and is also applicable to any form of bearing wherein the axle is adapted to rotate. It will also be obvious 35 that changes may be made in the details of construction and arrangement for the various applications of the bearing, said changes

being within the skill of the ordinary mechanician.

Having described my invention and set 45 forth its merits, what I claim and desire to secure by Letters Patent is:—

1. A journal box having a lubricant reservoir at its upper portion and a packing chamber disposed at its lower portion and 50 extending continuously upward at one side of said box longitudinally thereof and provided with a filling opening at its top, and a bearing block disposed in the upper portion of said box and provided with apertures 55 communicating with said reservoir.

2. A journal box having a lubricant reservoir disposed at its upper portion and a packing chamber disposed at its lower portion and having an extension for the length 60 of said box and continuously upward above the horizontal axis at one side thereof, an apertured bearing block disposed at the upper portion of said box and communicating with said reservoir, and a closure for the 65 extension from said chamber.

3. A journal box provided with depending longitudinally extending walls to form a bearing seat and a lubricating chamber having a passage extending transversely of the 70 seat to communicate with the central portion thereof and a packing chamber at the lower portion of said box having a continuous extension upward from the bottom thereof and longitudinally at one side of said box, 75 and a closure for an open end of said extension.

In testimony whereof I affix my signature in presence of two witnesses.

FREDERICK HELMICK.
